UNITED STATES PATENT OFFICE.

FRED H. BRIGMAN, OF PITTSBURGH, PENNSYLVANIA.

DESIGN FOR A BUTTON, FOB, OR SIMILAR ARTICLE OF JEWELRY.

43,838.

Specification for Design.

Patented Apr. 15, 1913.

Application filed December 5, 1912. Serial No. 735,145. Term of patent 14 years.

To all whom it may concern:

Be it known that I, FRED H. BRIGMAN, a citizen of the United States, residing at Pittsburgh, in the county of Allegheny and State of Pennsylvania, have invented a new, original, and ornamental Design for Buttons, Fobs, or Similar Articles of Jewelry, of which the following is a specification, reference being had to the accompanying drawing, forming part thereof.

The figure is a face view of a badge illustrating my design.

I claim:

The ornamental design for a button, fob, or similar article of jewelry, as shown.

FRED H. BRIGMAN.

Witnesses:

LETITIA A. MYERS,
ARCHWORTH MARTIN.
